UNITED STATES PATENT OFFICE

155,626

DESIGN FOR AN AERO-SPIN TOY

Joseph E. Perreault, Northampton, Mass.

Application December 15, 1947, Serial No. 143,157

Term of patent 7 years

(Cl. D34—15)

To all whom it may concern:

Be it known that I, Joseph E. Perreault, a citizen of the United States, residing at 7 Kingsley Avenue, Northampton, county of Hampshire, State of Massachusetts, have invented a new, original, and ornamental Design for Aero-Spin Toy, of which the following is a specification, reference being had to the accompanying drawing, forming part thereof.

Figure 1 is a plan view of an aero-spin toy, showing my new design, and Figure 2 is a side elevation.

I claim:

The ornamental design for an aero-spin toy, as shown.

JOSEPH E. PERREAUET.
